UNITED STATES PATENT OFFICE.

NATHL. CRADIT, OF RIPLEY, OHIO, ASSIGNOR TO CHESTER G. ROBINSON, OF SOUTH READING, MASSACHUSETTS.

LAMP.

Specification of Letters Patent No. 22,327, dated December 14, 1858.

To all whom it may concern:

Be it known that I, NATHANIEL CRADIT, of Ripley, Brown county, Ohio, have invented certain new and useful Improvements in 5 Lamps; and I hereby declare the following to be a full and exact description of the same, reference being had to the accompanying drawings, making part of this specification.

10 This invention relates to the class known as circular wick lamps and consists, 1st, in an arrangement of draft passages to maintain an equitable flow of air to the interior and exterior of the flame respectively and 15 to effectually consume volatile matters rising from the oil, and, 2nd, in an arrangement by which the wick may be inserted and regulated in height with equal facility to a flat wick.

20 Figure 1, is a perspective view of a lamp separated by an axial section. Fig. 2, is a horizontal section at *x*, Fig. 1. Fig. 3, is a horizontal section at *y*, Fig. 1. Fig. 4, is a detached perspective view of the outer portion 25 of the wick tube. Fig. 5, is a similar view of the inner portion.

A, is a screw neck of customary construction affording attachment for a perforated cylindrical ring B, called the lower screen. 30 C, is a floor separating the lower and upper draft passages 1, 2.

E, is a perforated cylindrical ring denominated the upper screen, which rests on a flange *b'* projecting from the exterior of 35 the lower screen B.

H, is the outer shell surrounding the wick.

I, is a conical or cylindrical tube within 40 which air is conducted to the exterior of the wick.

The wick tube is constructed as follows: The outer shell H, has the form below of a rectangular prism merging toward the upper end into the form of a truncated cone. 45 Within this shell is fitted a box K, M, P, Q, rectangular below and circular above as represented. The bottom K, of this box is perforated to permit the ascent of the combined air and gases from the reservoir into 50 the central draft passage also to admit the working of the rod or stem *l*, of the bottom L. The ends M, of the box fit tightly in the shell H, and support the shaft N, which is employed to elevate the button and the

shafts O, O', of the two sets of pinions 55 *o*, *o'* by which the wick is elevated or depressed. Between the sides P, and Q, of the box and the corresponding concavity of the shell are formed two flat passages 4 4' which unite in a single cylindrical or annular passage 5 above. The perforated bottom K, may be entirely dispensed with if desired.

Operation: The air to be supplied to the exterior of the wick enters through the upper screen E, and is deflected downward by 65 the tube I, passing under the lower end of the said tube and upward through the interior of the same to the top where it is deflected toward the flame. In the illustration here given the tube I, flares downward so as 70 to effectually arrest and equalize any sudden draft of air entering through the screen E. The air to supply the central draft enters through the lower screen B, and passes 75 downward through the ports 3 into the reservoir D, where it mingles with the gases rising from the oil and with them is drawn upward through the perforated floor K, to the interior of the tube Q, and is there by means of the button L, deflected toward the 80 flame.

The usual modes heretofore adopted for supplying the center draft have been either to conduct it through a bent tube from the top of the lamp down within the reservoir 85 and thence into the central tube or from below the reservoir up through a straight central tube as in the common Argand burner or as in the Knapp lamp through ports passing between the wicks and communicating 90 with the same perforations which supply the outside draft.

The advantages of my method of separating the outside from the center draft and conveying the latter through the cavity of 95 the reservoir are as follows: 1st. The flame is not materially affected by strong currents of air on the outside. 2nd. All the gases generated within the reservoir are drawn up through the central draft tube to the 100 flame and there consumed; which results in a better light from a lamp of given size, a saving of fuel and the avoidance of danger of explosion in case of the gases being entirely confined and of the inconvenience of 105 smoking when partially so. It is also found by experience that the burning of the gases from the oil tends to preserve the wick from

crustation and also prevents the escape of unpleasant effluvia.

It will be observed that by the described construction of wick tube in connection with the two rectilinear ranges of pinions around wick can be inserted and elevated with as much facility and precision as a flat one and either portion of the wick may if desired be burned without the other.

I claim as new and of my invention herein—

1. The described or equivalent arrangement of draft passages b 1 3 communicating with the oil reservoir; and central tube

Q, conducting the air and gases from thence to the interior of the wick as explained.

2. The box M P Q and shell H, in the described combination with two rectilinear sets of wick elevating pinions or their equivalents by which two flat wicks are converted into one circular wick as set forth.

In testimony of which invention I hereunto set my hand.

N. CRADIT.
